UNITED STATES PATENT OFFICE.

JOSEPH ABRAMOWITZ, OF NORTH VENICE, ILLINOIS.

BOOT, SHOE, OR THE LIKE.

1,272,172.

Specification of Letters Patent.

Patented July 9, 1918.

Application filed February 7, 1918. Serial No. 215,820.

To all whom it may concern:

Be it known that I, JOSEPH ABRAMOWITZ, a citizen of the United States, and a resident of North Venice, county of Madison, 5 and State of Illinois, have invented a certain new and useful Improvement in Boots, Shoes, or the like, of which the following is a specification, reference being had to the accompanying drawings, forming a part 10 thereof.

This invention relates generally to wearing-apparel and, more particularly, to a certain new and useful improvement in boots, shoes, or the like, the chief object of my 15 present invention being to provide a boot, shoe, or the like which will possess a neat appearance and be comfortable upon the foot, and which is made up of or comprises in its construction a relatively few parts, 20 whose designs or shapes facilitate and lessen the cost of assembling and finishing.

With the above and others objects in view, my present invention resides in the provision of a boot, shoe, or the like wherein the 25 outer sole with heel attached is formed as one complete unit or shoe-part, the inner sole and upper formed out of a single piece of material and without vamp or front, as another complete unit or shoe-part, and a 30 vamp or front with variable instep adjusting or adapting means, such as laces, buttons, and the like, as another complete unit or shoe-part, the shoe being substantially completely finished when the units stated are 35 assembled, and in certain novel features of form, construction, arrangement and combination of parts, all as hereinafter described and afterward pointed out in the claims.

In the accompanying drawings,—

40 Figure 1 shows, in plan, a low cut or half shoe, of a lace pattern, constructed in accordance with, and embodying, my invention;

Fig. 2 is a side elevational view of the shoe 45 illustrated in Fig. 1;

Fig. 3 is a fragmentary plan view, similar to Fig. 1, of a shoe of a button-pattern embodying my invention;

Fig. 4 is a fragmentary side elevational 50 view of the shoe illustrated in Fig. 3;

Fig. 5 shows in perspective my new shoe-part or unit comprising the upper and insole;

Fig. 6 shows in perspective my new shoe- 55 part or unit comprising the outsole, heel, and shank-stiffener;

Fig. 7 is a plan view of my new vamp of a lace pattern;

Fig. 8 is a plan view of a vamp of button-pattern;

Fig. 9 is a perspective view of a counter or inside quarter-facing; and

Fig. 10 is a perspective view of an outer facing-strip for the quarter-seam.

Referring more particularly to the said 65 drawings, in which like reference characters refer to like part throughout the several views, 1 indicates the outsole, which is preferably of a single piece of leather of suitable thickness and which embraces the ball, 70 shank, and heel portions. Secured by pegging, nailing, or otherwise to and upon the outer face of its heel portion, is a heel or lift 2; and suitably secured upon its opposite or upper face, is a shank-stiffener and arch-supporting member 3 preferably in the form of a strip of spring steel of a length to extend over the shank to a point upon the ball. These three elements, the outsole 1, heel or lift 2, and shank stiffener or arch-supporting 75 member 3, assembled as described, and save for heel-breasting, burnishing, and dressing, as may be desired in some instances, constitute one complete unit or shoe-part.

4 indicates or designates the insole, which 85 is shaped, to conform with the outsole 1, preferably upon a last or over shaping-dies or the like, and from whose margins are homogeneously integral upturned extensions forming the shoe-upper 5 over the toe, ball, 90 shank and heel of the insole 4, and which, as shown is full shoe height over the heel and at both sides along the shank, that is, its quarters 6 are complete and formed as integral extensions of the insole, and which upper is 95 less than full shoe height from a point at the intersection of the ball and shank and forwardly therefrom, including both ball and toe of the shoe. Such so-called cut away part of the shoe upper is indicated at 7 on 100 the drawings and will be hereinafter referred to as the ball and toe extensions. It will thus be seen that this unit or shoe-part is formed without vamp or front and made from a single piece of material, preferably 105 leather. In certain styles of shoes, as, for instance, those having relatively high quarters and made upon narrow lasts with heels or lifts whose arcuations are of relatively short radii, it will be found to be advantageous in the lasting to split the quarter vertically over the center of the heel and form

110

thereat a seam 8, as shown particularly in Fig. 5.

9 designates the vamp or front of the shoe, which is likewise preferably constructed of a single piece of suitable material, such as leather, and shaped at its side and front margins to conform with the margins of the ball and toe extensions 7 of the insole 4. If the shoe is of a lace-pattern, as in Figs. 1 and 2, the vamp 9 is kerfed for a portion of its length and along approximately its median line, as at 10, in Fig. 7, and eyeleted along each side of the kerf, as at 11, and to its underneath face is secured a tongue 12 arranged to underlie the kerf 10 and eyelets 11, as also seen particularly in Fig. 7. The rear margins of the vamp 9 on each side of the kerf 10 are suitably shaped to provide neat continuations of the upper margins of the quarters 6 and to extend over the instep.

The vamp 13, shown in Fig. 8, is substantially the same in form and construction as the vamp 9, except for its adaptation to the button-pattern of shoe. To that end, the vamp 13 is provided with a kerf 10' to one side of the median line thereof and provided with a button-holed flap 14 and co-operating buttons 15.

In such of the shoes as have the seam 8, and in order to produce a finished appearance thereto, I provide a strip 16 of leather or other suitable material, which, as seen particularly in Fig. 1, covers said seam and has its sides stitched to the quarter or upper on each side of the seam, the strip 16 having its lower end extended to be placed and secured between the insole and outsole when the shoe is assembled. And especially for shoes of this type, I provide an inside quarter-facing or counter 17, shown particularly in Fig. 9, which is of a shape substantially similar to an ordinary counter, and which is preferably of relatively soft, thin material, thereby serving not only as a cushion for the foot at this portion of the shoe, but also as a means for concealing or obscuring the quarter-seam 8, the counter 17 being secured in place as by stitches 18, shown best in Fig. 2.

In the assembling of a shoe constructed in accordance with my invention, a completed unit comprising an outsole, a heel or lift, and a shank-stiffener, is selected. Then a second unit comprising an insole and upper corresponding in size and shape to the first unit is selected, and the two units secured first at their heel portions by nailing. From their heel portions forwardly, including both margins of the shanks, both margins of the balls, and the margins of the toes of the insole and outsole, are stitched together, as partly indicated at 19 in Fig. 1, which stitching, by reason of the absence of a vamp, shoe-front, or any part overlying the insole, and with the shoe-upper having

throughout substantially vertical quarters and ball and toe extensions, may be readily and conveniently accomplished on an ordinary sewing machine. The vamp unit, either button or lace-pattern, is then secured, preferably by a butt-seam and machine-stitches, to the margins of the ball and toe extensions 7 of the insole, as seen in Figs. 1, 2, 3, and 4.

A shoe made and constructed in accordance with my invention comprises few parts or units readily and quickly assembled, may be conveniently manufactured at relatively low cost, has a neat, pleasing appearance, and is especially comfortable and easy upon the foot.

It is to be understood that the shoe may be made in various sizes and shapes and that minor changes in the form, construction, arrangement, and combination of the several parts thereof may be made and substituted for those herein shown and described without departing from the nature and principle of my invention.

Having thus described my invention, what I claim and desire to secure by Letters Patent is:

1. In a shoe, a unit integrally comprising an insole and an upper, the upper including side quarters and ball and toe extensions, and a longitudinally kerfed vamp-unit having instep adapting means disposed between said extensions and overlying the ball of the insole, the vamp-unit conforming throughout its side and front margins with the margins of said extensions and being thread-stitched throughout its side and front margins to the margins of said extensions.

2. In a shoe, a unit integrally comprising an insole and an upper, the upper including side quarters and ball and toe extensions, and a longitudinally kerfed vamp-unit having instep adapting means disposed between said extensions and overlying the ball of the insole, the vamp-unit conforming throughout its side and front margins with the margins of said extensions and being thread-stitched throughout its side and front margins to the margins of said extensions, the rear margins of the vamp-unit on each side of said kerf conforming to and providing continuations of the upper margins of the side quarters.

3. A shoe comprising an outsole, an insole overlying and secured to the outsole, an upper, the insole and upper being formed of a single piece of material and the upper including side quarters and ball and toe extensions, and a longitudinally kerfed vamp having instep adapting means disposed between said extensions and overlying the ball of the insole, the vamp conforming throughout its side and front margins with the margins of said extensions and being

thread-stitched throughout its front and side margins to the margins of said extensions, the rear margins of the vamp on each side of said kerf conforming to and providing continuations of the upper margins of the side quarters.

4. In a shoe, an outsole, an insole overlying and secured to the outsole, an upper, the insole and upper being formed of a single ¹⁰ piece of material and the upper being split

and stitched vertically over the center of the heel of the outsole, and a heel-counter fixed exteriorly upon the upper and concealing said stitch, the counter having an end extension disposed and secured between the out- ¹⁵ sole and insole.

In testimony whereof, I have signed my name to this specification.

JOSEPH ABRAMOWITZ.
